TREE SUSPENSION GRENADE DEVICE

Carl R. Weinert, West View, Pa., assignor to
Federal Laboratories, Inc., Pittsburgh, Pa., a
corporation of Delaware

Application July 25, 1945, Serial No. 606,908

6 Claims. (Cl. 102—65.2)

1

This invention relates to a tree suspension grenade device of the kind wherein a grenade containing a signaling charge or other charge can be launched into the air and entangled in a tree.

The invention will be described as employing a smoke grenade which may be launched and entangled in a tree so as to be readily visible to air observers. However, the invention is useful in entangling other grenades such as fragmentation grenades, high explosive grenades, white phosphorus grenades, gas grenades, etc., in attacking enemy concealed in trees.

In the accompanying drawings which illustrate a preferred embodiment of my invention,

Figure 1 is a side elevation of the grenade device in position on a launcher placed on the end of a muzzle of a rifle and ready for launching into the air;

Figure 2 is a vertical section through the cartridge containing a folded cord and weight; and

Figure 3 is a plan view of the expandable ring which forms a part of the means for preventing the grenade firing mechanism from operating until the grenade is launched into the air.

Referring more particularly to the accompanying drawings, the grenade 2 may be of any suitable kind, as for example, a hand grenade containing a smoke emitting charge. The grenade has the usual firing mechanism including a safety pin 3 and a safety pin ring 4 and a safety lever 5. When the safety pin 3 or the lever 5 is in the position shown in Figure 1, the grenade firing mechanism cannot operate. The lever 5 is held against the grenade by a ring 6. This ring is formed by a metal strap portion 7 and a spring 8 connected to the ends of the portion 7. In launching the device, the ring 6 slides downwardly over the grenade body thereby releasing the lever 5 and allowing the grenade firing mechanism to operate.

An adapter 9 has a tubular portion 10 and spring fingers 11 which fit over a bead 12 formed at the bottom of the grenade thereby connecting the grenade and adapter. The adapter has an annular stabilizing fin 13. The adapter receives a launcher 14 which is clamped on the end of a gun muzzle 15. The launcher has rings 16 which make a friction fit with the interior of the tubular portion 10 of the adapter.

A cartridge 17, connected by a strap 18 to the grenade, contains a folded cord 19. One end 20 of the cord is connected to a weight 21 and the other end 22 of the cord is connected to the strap 18 or grenade 2. The bottom of the cartridge 17

2

is crimped in as shown at 23 to support the weight 21.

The cartridge 17 at its top has a metal cap 24 of usual construction and a primer 25. An explosive charge 26 is located below the primer and adapted to be ignited by the primer. The charge 26 is held in place by a wad 27. A tube 28 is secured to the top of the cap 24, the tube containing a sleeve 29 and a firing pin 30. A safety pin 31 connected to a safety pin ring 32 extends through holes in the tube 28, sleeve 29 and firing pin 30. A shear wire 33 also extends through holes in the tube 28, sleeve 29 and firing pin 30.

The operation of the signaling device is as follows. When a blank cartridge is fired in the gun having the muzzle 15 the gases cause the grenade 2, cartridge 17 and adapter 9 to be projected into the air, the adapter sliding over the launcher 14 which remains fixed to the gun

muzzle 15. The force exerted upon launching the device causes the expandable ring 6 to slide down over the surface of the grenade 2 thereby releasing the lever 5 and allowing the grenade firing mechanism to operate. It will be understood that before the device is launched the grenade firing mechanism safety pin 3 and the cartridge firing mechanism safety pin 31 have been removed. The release of the lever 5 causes the firing mechanism to operate and the grenade 30 to emit smoke. The force exerted upon launching the device also causes the firing pin 30 of the cartridge 17 to shear the wire 33 thereby allowing the firing pin to strike the primer 25 and to ignite the explosive charge 26. The ignition of the charge 26 causes the wad 27, cord 19 and weight 21 to be expelled from the cartridge. When the weight 21 leaves the cartridge, it uncirms the crimp 23. The extension of the cord and the displacement of the weight in relation 40 to the grenade presents a length of cord 19 which may entangle in a tree thereby suspending the signaling device in the tree.

It will be understood that when the device is launched, the grenade 2 and adapter 9 remain 45 connected together. Thus the spring clip 11 is merely a convenient means for connecting the adapter and grenade. If desired, the grenade and adapter could be made as one unit.

The invention is not limited to the preferred 50 embodiment which has been given merely by way of illustration, but may be otherwise embodied or practiced within the scope of the following claims.

I claim:

55 1. A tree suspension grenade device compris-

ing a grenade containing a charge, a firing mechanism for the grenade charge, locking means for the grenade firing mechanism, a cartridge connected to the grenade, a folded cord and a weight and an explosive charge in the cartridge, a firing mechanism for exploding the cartridge charge, one end of the cord being connected to the weight and the other end of the cord being connected to the grenade, the grenade firing mechanism and the cartridge firing mechanism being operative upon launching the device to ignite the grenade charge and to explode the cartridge charge and expel the cord and weight from the cartridge so that the cord may entangle in a tree.

2. A tree suspension grenade device comprising a grenade containing a charge, a firing mechanism for the grenade charge, locking means for the grenade firing mechanism, said locking means including a ring slidable relative to the grenade to release the grenade locking means upon launching the device, a cartridge connected to the grenade, a folded cord and a weight and an explosive charge in the cartridge, a firing mechanism for exploding the cartridge charge, one end of the cord being connected to the weight

10

15

25

and the other end of the cord being connected to the grenade, the cartridge firing mechanism being operative upon launching the device to explode the cartridge charge and expel the cord and weight from the cartridge so that the cord may entangle in a tree.

3. A tree suspension grenade device according to claim 2, in which the slidable ring of said locking means is expansible.

4. A tree suspension grenade device according to claim 2, in which the slidable ring of said locking means includes a spring.

5. A tree suspension grenade device according to claim 1, in which the cartridge firing mechanism includes a firing pin and a shear wire holding the firing pin, the shear wire adapted to be sheared by the firing pin by the force exerted upon launching the device.

6. A tree suspension grenade device according to claim 2, in which the cartridge firing mechanism includes a firing pin and a shear wire holding the firing pin, the shear wire adapted to be sheared by the firing pin by the force exerted upon launching the device.

CARL R. WEINERT.
